FRITZ ALDENDORFF, OF BERLIN-WILMERSDORF, GERMANY; CHARLOTTE ALDENDORFF HEIRESS OF SAID FRITZ ALDENDORFF, DECEASED.

ELECTRICAL SWITCH.

Application filed August 26, 1924, Serial No. 734,290, and in Germany September 12, 1923.

This invention relates to an arrangement for setting shafts particularly for electrical switches and more particularly for electro-mechanical telephone systems.

5 The arrangement according to the invention comprises two co-axial shaft members adapted to be always turned in one and the same direction and one of which is normally held against rotary movement by an electro-magnetically operated shaft stepping pawl, whilst the other is normally held against rotation by the armature of an electro-magnet. The one shaft member may have a stepping wheel fixed thereto which is normally held 10 against rotation by the stepping pawl and the other shaft may be hollow and journaled upon the first shaft member and fixed to a notched member which is held against rotation by the said armature. One of the shaft 15 members may carry a coupling member adapted to couple the two shaft members together when one shaft (or the shaft members) is, or are, turned through any desired angle. The notched member fixed to the hollow shaft may be made in the form of a spider that is held against rotation by an electro-magnetic armature engaging with a leg of the spider. The coupling member carried by the other shaft member may be adapted to also 20 engage with a leg or legs of the spider and to thus couple the shaft members together. The arrangement for setting shafts in accordance with one feature of the invention may consist of two co-axial shafts one within the other, a 25 wheel or notched disc fixed to each shaft and a coupling member for coupling the shafts together which is pivoted on one wheel or disc so that its free end engages with the other wheel or disc when the shafts are coupled together. The coupling member may be in the 30 form of a pivoted electro-mechanically controlled armature shaped at its free end in the form of a rigid member that enters a notch in the notched member fixed to the other shaft 35 when the armature is released by its electro-magnet. The rigid member that enters a notch has the form of a tongue whose lateral edge (or edges) projects further out than its middle part so that, in a coupling operation, 40 a lateral projecting edge may enter into the notch before its sides register with the sides of the tongue. An electrical brush or brushes may be carried on by one of the shaft members and fixed contacts may be provided 45 which are wiped over by the brush, the said

electro-magnet being energized by currents sent through the wiper and the brush or through a contact which is closed whenever the brush carrier reaches a certain position with respect to the contact bank of a switch 60 in which the arrangement for setting shafts is used. The rigid coupling member may normally couple the two shaft members together and be caused to uncouple them when current is sent through the magnet that controls the 65 said coupling member. The two coaxial shaft members may be interconnected by a spiral spring which, when wound up by rotation of the one shaft member applies a torque to the other shaft member. This feature of 70 invention is, in itself, old but forms a part of a novel and useful combination in connection with arrangements or switches in accordance with the present invention.

Another feature of the invention consists 75 in a switch with a wiper arranged to move over bank contacts and provided with arrangements for stopping the wiper at a certain point, which arrangements comprise a stopping magnet operated by a current whose 80 duration of flow or interruption is determined by the speed of the wiper and by the number of bank contacts brought into the electrical condition for actuating the stopping magnet. A high speed electric switch 85 is thus obtained with wipers adapted to be stopped at any desired position, in which the wiper stopping magnet is actuated by placing a certain potential on any desired set of magnet-affecting bank contacts swept over by a 90 wiper in a wiper stopping circuit, the said potential being applied to as many bank contacts as are necessary to make the time of travel of the wiper over effective magnet-affecting contacts equal to the time of response of the said magnet. Switches arranged in the aforescribed manner may 95 be used as line finders, group selectors or connectors in electro-mechanical telephone systems. In such systems the coupling magnet of a group selector or connector has numerical impulses sent through it from the contacts of an impulse relay controlled by subscribers' dialling impulses. The impulses from the contacts of the impulse relay may be 100 sent through bank contacts of the selector or through a contact which is operated whenever the brush carrier reaches a certain position with respect to the contact bank.

In accordance with another feature of my 110

invention a switch may be provided having a brush carrying member subjected to a driving force, a detent which stops the movement of the brush carrying member whenever the 5 brushes have executed a certain amount of movement, an electro-magnet for operating the said detent, and an energizing circuit dependent on the position of the brush carrier for affecting the electro-magnet in such a 10 way that the detent is always caused to stop the brushes whenever they have been driven a certain distance. The brush carrying member may be driven by a continuously acting force such as a spring. The switch in accordance with this feature of invention may be provided with brush stopping members that cooperate with an electrically actuating detent that moves into the path of the brush stopping member in response to current 15 impulses whose circuit depends on the position of the brush carrier. A contact in the circuit of the detent actuating magnet may be operated by a part attached to the brush carrier.

Another feature of the invention consists 20 of a method of wiring the contacts of contact banks of groups of selectors with 50 or more brush positions.

The invention is shown in the drawing in which

30 Fig. 1 is a perspective view of a selector for electro-mechanical telephone exchanges in which the arrangement for setting shafts in accordance with the invention is used.

35 Fig. 2 is a side view of the selector shown in Fig. 1.

Fig. 3 is a more or less diagrammatic perspective view of the shaft setting arrangement and of the coupling members for coupling the shaft sections and of the members 40 for setting them in operation.

Fig. 4 is a section through the shaft sections one of which carries a set of wipers or brushes,

45 Fig. 5 is a perspective view of a stepping wheel which is fixed to one of the shaft sections and to which the coupling member, in the form of an electro-magnet armature, is pivoted.

50 Fig. 6 shows fragments of bank contact levels of which the contact bank of a switch is built up.

Fig. 7 is a perspective view of the wiring of a group of contact banks belonging to three different switches.

55 Fig. 8 shows the circuits of a line finder and a group selector in accordance with Figs. 1-6.

Fig. 9 illustrates the circuits of a connector constructed in accordance with Figs. 1-6.

60 Figs. 10 and 11 shows circuits by which the speed at which the wipers of a switch according to Figs. 1-3 are driven may be still further increased.

65 Figs. 12-15 show a modified form of switch in which only two magnets instead of three

are employed. This switch may be used as a group selector or connector or as a line finder if a contact bank of the speed shown in Figs. 1 and 3 is employed.

Figs. 16 and 17 show a method of building up contact banks and a manner of shaping the soldering tabs of the bank contacts that permit of the interconnection of bank contacts of adjacent switches by means of straight or stretched wires. 75

The operation of the arrangement for setting shafts and more particularly switch shafts will now first be described with reference to Figs. 3-5. In Fig. 4 the shaft sections 1 and 2 and the magnet 4 for controlling the relation between the shaft sections are shown mounted upon a part 3 of the frame of the switch. The magnet 4 has a cylindrical iron shell and a hollow central core 5 into whose bottom end a screw 6 is inserted.

Journalled in the hollow core 5 is a shaft section 1 which rests upon a ball 7. The bottom surface of the shaft 1 which abuts upon the ball 7 and the top surface of the screw 6 is tempered to prevent cavities being formed by the friction of the ball 7. Fixed to the shaft 1 is a disc 8 and a stepping wheel 9.

Journalled on the shaft 1 is a hollow shaft or slip 2 with which a notched disc or spider 10 is fixed. The hollow shaft 2 together with the spider 10 carries brushes 11, of which only one is more or less diagrammatically shown in Fig. 3. At the top of the shaft 1 there is a

spring box 12 which contains a spring 13 whose one end is fixed to the periphery of the spring box 12 whereby it is unyieldingly attached to the shaft 1, while its second end is fixed to the hollow shaft 2. When the shaft 1 is turned in the direction of the arrow 22 the spring 13 is wound up so as to produce a

90 torque which acts upon the hollow shaft 2 so as to tend to move the latter also in the direction of the arrow. The hollow shaft, however, is normally prevented from turning by the armature 14 of the magnet 15, which engages with a leg 16 of the spider 10. The shaft 1 is normally prevented from turning by a stepping pawl 17 engaging with a tooth

95 of the wheel 9, the pawl 17 abutting upon a stop or stroke limiting member 20 which prevents the pawl 17 from being deflected beyond a certain point in the direction of the arrow 21. The rotation of the stepping wheel 9 in the direction opposite to that of the arrow 22 is prevented by a detent 19. The

100 spring 13 is wound up by sending current impulses through the magnet 18. When the magnet 18 is excited in this manner its armature 23 together with the lever 24 and the stepping pawl 17 attached thereto oscillates so

105 that, at each attraction of the armature 23, the pawl engages with another tooth of the wheel 9 and at each detraction a spring 25 pulls the lever with the stepping pawl 17 forward so that the pawl rotates the disc 9 the

110

115

120

125

distance of one tooth in the direction of the arrow 21. During the rotation of the wheel 9 and of the shaft 1 fixed to this the spring 13 is wound up because its inner end is connected to the hollow shaft 2 which is held stationary by the leg 16 and the armature 14 engaging therewith.

Pivots mounted on the stepping wheel 9 is an armature 27 of the magnet 4. By a spring 50 the free end or coupling member 28 of the armature is normally pressed upwards so that the coupling member 28 lies between two legs 16', 16'' of the spider and thus couples the shaft 1 with the hollow shaft 2.

It will now be assumed that the brush 11 is to be turned through a certain angle, for example, to such an extent as will result in the brush 11 coming to a stand-still on the contact 26. To this end the magnets 4 and 15 are both energized which results in the coupling member 28 being pulled out from between the legs 16', 16'' and in the armature 14 being disengaged from the leg 16 of the spider 10. The spring 13 can now rotate the hollow shaft 2 in the direction of the arrow. This rotation continues only as long as the coupling magnet 4 is kept energized and this energization is effected by a current which flows through the magnet 4, brush 11 and contacts like 29. As soon as the brush 11 reaches a dead contact, say for example contact 30, the current flowing through the magnet 14 and the brush 11 is interrupted so that the magnet releases the coupling member 28. This latter flies upward and first wipes against the leg of the spider which happens to be passing the member 28 at that moment. As soon as this leg has slipped past the projection 31 of the member 28 this latter is pushed therefore up by its spring so that the right hand edge of the projection 31 gets into the path of the next spider leg. When this next leg strikes against the side of the projection 21 the member 28 is pushed up still further by its spring so that the left or opposite edge of the member 28 moves up into engagement with the leg 16' with which it registers. The upward movement of the member 28 between two adjacent legs requires a certain time and this time is gained by making the dead contact, for example 30, over which the brush 11 wipes, of such length that sufficient time is gained for the described coupling action. When the coupling operation is completed the brush 11 will rest upon a contact like 26 between two long contacts like 30 and 33.

The rotation of the hollow shaft with the brush 11 in the described manner results in the spring 13 being detensioned or running down to a certain extent. The spring 13 is rewound by energizing the magnet 15 so that its armature reengages with a leg of the spider 10, in energizing the magnet 4 so as to withdraw the coupling member 28 from the spider and in simultaneously sending current

impulses through the stepping magnet 18 in order to rotate the stepping wheel with the shaft 1 and the spring box 12 in the direction of the arrow 22. When the stepping wheel 9 has been rotated sufficiently to completely 70 rewind the spring 13 the magnet 18 is deenergized by a switch which is always operated when the wheels or discs 9 and 10 occupy a certain angular position in respect to each other.

The setting of the shaft sections 1 and 2 with respect to each other and of the brush 11 with respect to its contact bank having now been described with reference to Figs. 3, 4 and 5, the operation of the switch or selector for semi-automatic or automatic telephone systems shown in Figs. 1 and 2 will now be understood. The selector has a frame comprising two lateral parts 3², 3³ with a bottom bent bridge piece 3 and a top bridge piece 3¹. The lower bridge 3¹ carries the coupling magnet 4 whose magnetic circuit is formed in the shape of an iron pot or cylinder with a middle core, and the upper bridge carries a journal bracket 44 for the shaft 1. The lower portions of the lateral parts 3², 3³ are formed in the shape of broad lugs or ears upon which the magnets 5 and 18 are mounted. The contact bank 36 is connected to the lateral parts 3², 3³ of the frame by means of screws 34 and 35. The contact bank has four rows of bank contacts which are constructed as shown in Fig. 6. The bank contacts of each row or layer, for example the contacts 33, 26, 30 of each row are embedded in insulation 37¹, 37², 37³, 37⁴. The contacts of the one row 37¹ are of different lengths. Between every two long contacts 30, 33 there is a short or narrow contact 26. The contacts of the row 37² are all shaped in the form of straight narrow strips 38. The contacts 39 of the row 37³ all extend radially from a common center to a certain distance therefrom where they bend in an oblique direction towards the left. The contacts 40 of the row 37⁴ also extend radially from a common center to a certain distance where they bend obliquely towards the right. The contacts 33, 26, 30 of the row 37¹ also extend along a straight line through the insulation 37¹ to a certain distance beyond the insulation where they bend towards the left when the contact rows are all in position in the switch. The circle where the bends of these latter contacts are rotated is within the circle that passes through the bends of the contacts 39, 40 so that they form soldering lugs 34 which register with the spaces between the straight parts of the contacts 39, 40. By this construction it is made possible to interconnect all corresponding contacts of switches mounted beside each other by means of straight bare wires as shown in Fig. 7.

The construction and general operation of the arrangement for setting shafts and of the

switches in which this arrangement is used having now been described an electro-mechanical telephone exchange in which the elements shown in Figs. 1-7 are employed will 5 now be described with reference to Figs. 8 and 9 in which the circuits of such an exchange are diagrammatically shown. In Fig. 8 the circuits of a line finder 100 and of a group selector 200 are shown. Fig. 9 illustrates circuits of a connector 300. In the line finder circuits the starting magnet 15, coupling magnet 4 and the stepping magnet 18 have the same reference numerals as in Figs. 1 and 3. In the group selector 200 the coupling magnet is designated by 204, the starting magnet by 215 and the stepping magnet by 218, while in the connector circuits, Fig. 9, 304 indicates the coupling magnet, 315 the starting magnet and 318 the stepping magnet.

The operation of the circuits of the switches will be understood from the following description of the operations which occur in establishing a connection through the exchange. It will be assumed that subscriber 101 wishes to establish a connection with a subscriber 232.

The subscriber 101 raises his receiver from the hook and a current then flows from the positive pole through the line relay 102, contact 103 of the cut-off relay 104, wire 105, sub-station 101, wire 106, contact 107 of the cut-off relay to the negative pole. The line relay is thus energized and at its contact 108 closes a circuit which extends from the positive pole through 108, group relay 109 to the negative pole. The group relay which is common to a sub-group of subscribers, closes its contact 110 and thus sends a starting impulse through the wire 111 which flows partly through 112, resistance 113, relay contact 114, starting magnet 15 to the negative pole and partly through the coupling magnet 4, relay contact 115, brush 116, bank contact 120, wire 121, relay contact 122, wire 123, relay contact 124 to the negative pole. By this means the brushes 116, 117, 118, 119 are released by the starting magnet 115 and the coupling magnet 4, so that the spring 13, Fig. 3, drives the brushes at a high speed over the bank contacts, this motion continuing as long as the coupling magnet 4 remains energized. The coupling magnet 4 receives current as long as the brush 116 continues wiping over live contacts like 125, that is contacts which are connected to the negative pole. As the contact 126, however, has been disconnected from the negative pole through the opening of the contact 127 of the relay 109 the magnet 4 will be deenergized when the brush 116 reaches the contact 126 so that the coupling member 28, Fig. 3, is released by the magnet 4 and the brush 116 is stopped when it reaches the short contact 128 adjacent the contact 126. A weak current then flows through the coupling mem-

ber 4 and the changeover relay 129, this current being sufficient to cause the coupling magnet to attract its armature. This current flows from the positive pole through 110, 111, contact arm 130, 112, 4, 115, 116, 128, 121, 129 to the negative pole.

It is to be noted that as long as the selector 100 is in its normal position the relay 129 is short circuited by a wire which leads through the relay contacts 124 and 224. This short circuit is, however, opened as soon as the selector 100 is started, because a switch 131 in the selector is then closed to complete a circuit from the positive pole through 131, 132, relay contact 233, right hand winding of a relay 235. The relay 234 opens its contact 224 and thus removes the short circuit that bridges over the relay 129, so that the latter can be energized by a current flowing through the coupling magnet 4 and the contact 128 in the other described manner.

When the relay 129 is thus energized, it closes its contacts 135, 136, 137 and opens its contacts 129, 115. When the contact 115 is opened the coupling magnet 104 which had already been partly deenergized so that it was not capable of keeping its armature attracted, is completely deenergized. By the closure of the contact 135 a locking circuit for the relay 129 is closed through 132 and 131. At the contact 136 an energizing circuit which is closed later is prepared for the coupling magnet 4, and at contact 137 the circuit of the stepping magnet 18 is closed, this circuit extending from the negative pole through the interrupter 140, 137 and relay contact 141 to the positive pole. The stepping magnet 18 now moves the brushes 116-119 step-by-step until the brushes 117, 118, 119 reach the bank contacts 142, 143, 144. As soon as this happens the stopping relay or test relay 145 is energized by a current which flows from the positive pole through 110, 130, 115¹, 145, 117, 142, closed contact 146 of the line relay 102, cut-off relay 104, to the negative pole. The relay 145 closes its contacts 147, 148, 149, 150, 151 and opens contact 141, the latter opening the circuit of the stepping magnet 118, so that the brushes 116, 117, 118, 119 stop on the contacts 142, 143, 144. The energization of the stepping relay 145 is accompanied by the energization of the cut off relay 104. This latter opens its contacts 103, 107 and closes its contact 152 so that, after the line relay 102 is deenergized, the energizing current of relay 145, instead of flowing through contact 146, flows through contact 152 and the relay 104 to the negative pole. The subscriber 101 is now connected through brushes 117, 118, contacts 147, 148 and contacts 253, 254 to the impulse relay 255 of the group selector 200.

The impulse relay 255 closes its contacts 256, 256¹, the contact 250 completing an energizing circuit for the release relay 258

which extends through the resistance 259. The relay 258 closes a locking current for itself at its contact 260 and at its contact 261 it closes a circuit for the relay 160 which 5 thereupon closes its contacts 161, 162, 163, 164, 165 and opens the circuit of the starting magnet 15 at contact 114. By its contacts 162, 164, the relay 160 prepares an energizing circuit for the coupling magnet 4 which is closed 10 when the switch 100 is restored on the deenergization of the release relay 258 in the manner more fully described hereinafter. At its contact 163 the relay 160 prepares a short circuit for the test relay 145 which is closed through 15 contact 264 of the release relay 258 as herein-after described on the initiation of the restoration of the switch 100. At contact 165 the relay 160 closes a circuit which extends through the contact arm 166 of the trunk finder TF and through the upper winding of the relay 167, whereby the relay 167 is caused to close its armature contacts 168, 169. A current then flows from the negative pole through the interrupter 170, contact 169, driving 20 magnet 171 to the positive pole. The driving magnet now rotates the brushes 166, 130 of the trunk finder TF step-by-step until the wiper 160 encounters a conductor for example 172, which is not connected to the negative pole through the contact of a relay corresponding to the relay 160. At this moment the relay 167 allows its armature to drop back so that the circuit of the magnet 171 is opened at contact 169. The wipers 166, 130 of the 25 trunk finder will now stand on a free trunk so that the line finder associated with this trunk will be started through the starting wire 111 when the next subscriber calls. The energization of the relay 167 during the travel of the wiper 166 from one bank contact to another is ensured by the lower winding of 167 which, at each impulse sent through the magnet 171, also receives an impulse through the contact 168, this impulse flowing from the negative pole through 170, 168, lower winding of 167 to the positive pole. 30 The energization of the impulse relay 255 gives rise not only to the energization of the release relay 258 but also to the energization 50 of the starting magnet 215 of the group selector 200 by a current extending from the negative pole through 256, wire 263, wire 264, 215, to the positive pole. On the calling subscriber 101 now sending in two numerical impulses, two oscillations of the impulse relay armature will be caused thereby and at each 55 detraction of this armature a current flows from the negative pole through contact 260, contact 268, 257, wire 269, contact bank connections 270, wiper 275 of the group selector, coupling magnet 204 to the positive pole. At the first impulse through 204 this magnet is caused to attract the coupling member of the group selector (corresponding to 28, Figs. 3, 60 4 and 5) so that the driving spring (corre- 65 sponding to 13, Figs. 3 and 4) flings round the wipers to 272, 273, 274, 275. As soon as the wiper 275 leaves the contact 276 the magnet 204 is deenergized, this deenergization taking place even if the impulse through contacts 268, 267 has not ceased, so that the coupling magnet 28, Fig. 3, is jerked up again by its spring and the wipers will thus be stopped as soon as the wiper 275 reaches the contact 277 located between the two adjacent long bank contacts. At the second oscillation of the armature of the impulse relay 255 another impulse flows through 260, 268, 267, 269, 277, 275 and through the coupling magnet, this impulse giving rise to another attraction of the coupling member 28 by its magnet, thus allowing the brushes 272, 273, 274, 275 to be flung round onto the contact 278. When the brush 275 reaches the contact 278 the brush carrier is recoupled by the coupling member 28 to the stationary central shaft of the selector. Another excitation of the coupling magnet 204 does not take place because in the meantime the impulse relay 255 will have again attracted its armature so as to open the contact 268. 70 80 85 90 95 100 105 110 115 120 125 130

It is to be noted that during the oscillation of the armature of the impulse relay 255 the contact 256¹ is opened at each armature oscillation. Consequently the changeover relay 266 receives current impulses that flow from the negative pole through 260, 266, resistance 279, to the positive pole and cause the changeover relay to maintain its armature energized as long as the armature of the impulse relay 100 continues oscillating. Thus contact 257 is kept closed and the contacts 280, 281 are kept open as long as the armature of the impulse relay oscillates.

When the subscriber has sent in his 100 selecting impulses for setting the group selector 200 onto the proper bank contact group, the oscillations of the impulse relay armature cease and the contact 256¹ is kept closed for a comparatively long interval during which it 110 continuously short circuits the changeover relay 266. This relay is thus made to let its armature drop back so as to close at its armature 280 a circuit extending from the negative pole through 280, left hand winding of relay 282 and the off-normal switch 265, whereby the relay 282 is energized and made to close its contacts 283, 284, 285, 286 and to open contact 287. The off-normal switch 265 is closed as soon as the two shaft sections of the group selector are moved out of their normal positions relatively to each other and this happens as soon as the spring 13, which is tensioned by rotating the shaft section 1, Figs. 3 and 4 relatively to shaft section 2, 125 as hereinbefore described, rotates shaft section 2, round shaft section 1 in response to the selecting impulses of the calling subscriber.

As soon as the changeover relay 266 is de- 130

energized and the relay 288 is energized in the manner described current impulses flow from the negative pole through 288, 281, 283, 289, and through the stepping magnet 218 to the positive pole. By this means the two shaft sections together with the wipers 272, 273, 274, 275 are all rotated step-by-step until a free trunk such as 309, Fig. 9, is reached. A current then flows from the negative pole through contact 284 of relay 282, relay contact 290, test relay 291, test brush 274, test contact 292, wire 302, wire 303, contact 304, resistance 305 to the positive pole. The test relay is thus energized to close its contacts 293, 294, 295, 296 and open its contacts 253, 254. By the closure of contact 296 the relay 284 which was deenergized by the opening of contact 233 again received current which flows from the positive pole through the left winding of impulse relay 255, left winding of 234, contact 296, right hand winding of impulse relay 255 to the negative pole. By this means the impulse relay 255 is kept energized and also the relay 234 is energized so that it interrupts the circuit of the stepping magnet 218 at contact 289 and closes a locking circuit for itself at its contact 297, said circuit extending from the negative pole through the right hand winding of 244, 297, off-normal switch 265 to the positive pole.

The calling subscriber is now connected through contacts 293, 294 to the impulse relay 355 of the connector, this relay being energized by a current that flows from the positive pole through the left hand winding of 255, wire 305, bank contact 298, wiper 273, 294, 148, 118, 143, 106, station 101, 105, bank contact 145, wiper 119, 147, 293, 272, 299, 306, right hand winding of 355 to the negative pole.

The impulse relay 355 closes its contacts 307, 308. At contact 307 a circuit is closed for the release relay 238, this circuit extending from the negative pole through armature contact 309, 307, 358, resistance 310 to the positive pole. The relay 358 closes its contacts 311, 312 and opens its contacts 313, 314. By the closure of contact 311 the current path which is independent of the contact 304 is closed through the resistance 305, this current path maintaining the test relay 391 in the group selector 200 energized when the contact 304 of the relay 315 is opened in the manner hereinafter described.

Should the calling subscriber, who is now connected through the group selector 200 to the connector 300, now replace his receiver, the impulse relay 355 would be deenergized and, due to the detraction of the armature of the impulse relay, the changeover relay 316 would be energized by a current which, as soon as the contact 308 is opened, flows from the negative pole through 309, contact 312, changeover relay 316, resistance 317, to the positive pole. The relay 316 then completes at contact 318 a circuit extending from the negative pole through 309, 312, 319, 318, 320, wire 321, wiper 375, coupling magnet 304 to the positive pole. At the same time a current also flows from the negative pole through 309, 312, 302 to the release magnet 315. By this means the parts of the connector are brought out of their normal positions relatively to each other and the wipers 372, 373, 374, 375 are rotated by their driving spring until the coupling member, corresponding to 28 of Figs. 3, 4 and 5, stops the wipers at some intermediate contact, say 378. The shifting of the parts of the connector out of their normal positions results in the closure of the off-normal switch 365. Furthermore by the deenergization of the impulse relay 355 the contact 320 is closed which short circuits the release relay 358 so that it allows its armature to drop back, whereby the contact 312 is opened and contact 321 is closed, so that a current flows from the negative pole through 309, 321, left hand winding of relay 315', off-normal switch 365 to the positive pole. The relay 315 is energized to open its contact 304'. Since contact 311 is also opened the current flowing from the positive pole through 305, 302, bank contact 292 through the test relay 291 is now interrupted so that the test relay 291 allows its armature to drop back so as to deenergize the impulse relay 250 by opening contact 296. By this means the restoration of the group selector 200 to its normal position is initiated, the release relay being short circuited at contact 257 and thus caused to close its contact 233'. Current impulses then flow from the negative pole through 288, 233, armature contact 285, and the stopping magnet 218. At the same time the coupling magnet 240 is energized by a current flowing from the negative pole through the contact 265 of the release relay, contact 270' of relay 278', armature contact 286, 204 to the positive pole. The two shaft sections of the group selector are thereby uncoupled from each other so that the current impulses flowing through the stepping magnet 218 rotate the shaft section 1 (Figs. 3 and 4), while the shaft section 2 is held stationary by the armature of the starting magnet 215. The shaft section 1 is now rotated by the stepping magnet 218 and the spring of the group selector is thus wound up until the two shaft sections have been turned into their normal positions relatively to each other and the off-normal switch 265 is opened, whereby the relay 282 is deenergized. The relay 282 then opens its armature contact 286 so as to again deenergize the coupling magnet 204 and recouple the shaft sections 1 and 2 to each other. The stepping magnet 218 now receives further impulses which flow from the negative pole through 288, 233', contact 269' of switch 280', 218, to the positive pole. At the same

time the starting magnet 215 is energized by a current flowing from the negative pole through armature contact 287, contact 268' of switch 280', 215 to the negative pole. The 5 intercoupled shaft sections together with the brushes 272, 273, 274, 275 are now rotated further until they reach their normal position at the commencement of the contact bank and the off-normal switch 280' is opened so 10 as to interrupt the circuit of the stepping magnet 218 and the circuit of the starting magnet 215. The parts of the selector 200 will now be in their normal position.

It is to be noted that during the winding 15 up of the spring of the group selector that is during the step-by-step rotation of the shaft section 1 by the stepping magnet 218 and the simultaneous excitation of the coupling magnet 204 and deenergization of the starting magnet 215, the coupling magnet 204 after its initial energization is energized by current flowing through the contact 270' and resistance 250' so that the pull exerted of the armature 27 (Fig. 4) is weakened and only 20 a comparatively small pressure of the shaft 1 on its lower journal 7 takes place. The insertion of the resistance 250' in the circuit of the coupling magnet is effected by the relay 278' which opens the contacts 270' slowly when it is excited by a current flowing 25 from the negative pole through a contact 265', 278', switch 265 to the positive pole.

The deenergization of the release relay 258 also results in the rewinding of the spring 30 of the line finder 100. When the release relay 258 is deenergized the relay 145 is short circuited by the closure of the contact 264, which results in the closure of a short circuit extending through 240, 163, armature contact 149 35 of the test relay. The armature of the test relay is thus caused to drop back slowly. Before the armature of the relay 145 executes its backward travel, the coupling magnet 4 is energized by a current flowing from the negative pole through 263, 164, 136, 4, 151, 162, to the positive pole. The coupling magnet 4 attracts the coupling member of the line finder and thus uncouples the two shaft sections 1 and 2. As soon as the armature of the 40 release relay 145 drops back the contact 151 is closed and the armature of the coupling magnet 4 is then kept attracted by a comparatively weak current flowing through the resistance 113. The detraction of the armature of the relay 145 also results in the closure 45 of a circuit through the stepping magnet 18 of the line finder, extending from the positive pole through 141, 137, 18, 114, to the negative pole. The armature of the starting magnet 15 maintains the shaft section 2 stationary whilst the stepping magnet 18 turns the shaft section 1 and thus winds up the spring 13 (Figs 3 and 4) of the line finder, this rewinding operation continuing until 50 the switch 131 is opened when the spring

will be fully retensioned and at the same time the relays 160 and 129 will be deenergized. As soon as the relay 129 is deenergized, the circuit of the stepping magnet 18 is opened at the armature contact 137. The spring of the line finder having now been fully rewound, the line finder will be ready for renewed use. The connector which was brought out of its normal position is also restored in the following manner: On the contacts 293, 294, being 55 opened at the deenergization of the test relay 291, the impulse relay 355 is also deenergized and the release relay 358 short circuited through contact 320. The relay 358 closes at its contact 321 and energizing circuit for relay 315 extending from the negative pole through 301, 321, relay 315, switch 365 to the positive pole. The relay 315' closes at contact 322 a locking circuit for itself extending from the negative pole through its right hand winding, off-normal switch 365 to the positive pole. The relay 315' at its contact 323 also closes a circuit for the stepping magnet 318 (positive pole, 318, 323, 313, interrupter 324, negative pole) and at contact 325 it closes 60 a circuit for the coupling magnet 304 extending from the negative pole through contact 325, 314, 327, 304 to the positive pole. In the energizing circuit of the coupling magnet 304 a resistance 328 is inserted after a brief interval by the opening of the contact 327 by means of relay 326 which, immediately after the initial energization of the coupling magnet 304, is also energized by a current flowing from the negative pole through 325, 314, 100 326, 329 to the positive pole. Whilst the coupling magnet 304 is thus energized by a comparatively weak current which is only just strong enough to keep the coupling member attracted and while at the same time the starting magnet 315 is deenergized, the stepping magnet receives current impulses by which the shaft section 1 of the connector is rotated step-by-step until the switch 365 is opened and the relay 315' is thereby deenergized. When the relay 315' is deenergized the coupling magnet 304 and the relay 326 are also deenergized by the opening of contact 325. At the same time, the closure of the contact 313 of the deenergized relay 315' 110 results in the energization of the starting magnet 315, while the magnet 318 receives current impulses through contact 331 of switch 332 which flow from the negative pole through the interrupter 324, 313, 333, 331, 318 115 to the positive pole. The shaft sections 1 and 2 of the connector being coupled together on account of the deenergization of the coupling magnet 304, the two shaft sections together with the brushes 372, 373, 374, 120 375 are rotated together step-by-step until the switch 332 is opened upon the brushes 372 to 375 reaching their normal position when the circuit of the stepping magnet 318 is opened at contact 331 and the circuit of the 125 130

starting magnet 315 is interrupted at contact 334. The various parts which were taken into use as a result of the partially established connection have now been returned to 5 their normal positions.

It will now be assumed that the calling subscriber, whose connection has been extended to the connector, Fig. 9, proceeds with the establishment of the same and sends in a 10 series of tens impulses which effect the impulse relay 355 at each tens impulse, a current flows from the negative pole through 309, 312, 319, 318¹ of the changeover relay 316 which is kept energized during the oscillations of the impulse relay of 355, contact 320 15 of the relay 315 which is not yet energized, wire 321, contact 374¹, wiper 375, coupling magnet 304, to the negative pole. In response to the first tens impulse the spring 313 (Fig. 20) jerks the brushes 272-275 up to the bank contact 335. In response to the second and third tens impulses the said spring turns the wipers first to bank contact 336 and then to bank contact 337. The impulse relay 355 is 25 maintained energized for a comparatively long interval between the tens and units series of impulses, and during this period the changeover relay 316 is short circuited by contact 308 so that it opens its contacts 318¹, 338 and closes its contacts 339, 340. On the 30 closure of contact 339 the relay 315¹ is energized by a current which flows from the negative pole through 309, 312, 339, left hand winding of relay 315¹ to the positive pole. The relay 315¹ is energized to open its 35 contacts 320, 330, 304¹ and close its contacts 341¹, 342, 322, 323 and 325. The calling subscriber now sends in the units impulses, the number of which in the present instance is 2, thus giving rise to two deenergizations of the 40 impulse relay 355. The moment the relay 355 is deenergized in response to the first impulse the short circuit of the changeover relay 316 is removed at contact 308 so that the 45 changeover relay again attracts its armature. At each units impulse a current flows through the stepping magnet 318, its circuit extending from the negative pole through 309, 312, 319, 318¹, 342, 318 to the positive pole. The 50 shaft sections 1 and 2 which are coupled together and hence the wipers 372-375 are thus rotated two steps so as to cause the wipers 372-375 to land on the bank contact set 332. The units impulses having now ceased the 55 changeover relay 316 is again kept short circuited at contact 308 and thus caused to let its armature drop back. It is thus to be noted that on the deenergization of the changeover relay 316, when the first units 60 impulse was sent in, the relay 343 was energized by a current flowing from the negative pole through 309, 312, 338, 341, left hand winding of relay 343 to the positive pole. The relay 343 closed its contacts 344, 345, 65 346. Through contact 346 a locking circuit

is established for the relay 343 including its right hand winding and the contacts 312, 309.

On the changeover relay 316 being again short circuited through contacts 308 after the 70 units impulses have been sent in the deenergization of the same results in the negative pole of the battery being connected through contacts 309, 312, 339, 345 to the test relay 347. If the test brush 374 is in contact with a free test wire, that is to a wire upon which there is a certain positive potential, the test relay 347 will be energized to close its contacts 348, 349, 350, 351 and open its contact 352. By the closure of contact 348 the ringing relay 326 is caused to be periodically energized by current through an interrupter that sends impulses from the negative pole through 348, 326, contact 329 to the positive pole. At each energization of the relay 326 80 the ringing current generator 354 is connected through contacts 353, 355 to the called line so that the bell of the one subscriber rings. When the wanted subscriber responds by raising its receiver from the hook of his instruments the ringing cut-off and battery feed relay 356 is energized by a current flowing from the negative pole through the left hand winding of 356, contact 357, 349, wiper 372, one wire of the talking circuit 232 to the 85 call station, back through the other wire to the exchange, thence through 373, 350, 358, right hand winding of 356 to the positive pole. By the energization of relay 356 the ringing relay 326 is disconnected at contact 90 329. At the same time the relay 362 is energized by a current flowing from the negative pole through contact 361, left hand winding of 362, switch 365, to the positive pole. The relay 362 opens its contact 309 but only after 95 the negative pole is connected through 360 to the wire 363 and thus to the contact 312 to maintain the energization of the release relay 358. The relay 362 closes at its contact 364 a locking circuit for itself extending from 100 the positive pole through 365, right hand winding of 362, contact 364, 312, 360 to the negative pole. The calling and called subscriber can now converse through the wires 105 drawn in Figs. 8 and 9 with heavy lines. 110

If the called subscriber is first to replace his receiver at the end of the conversation the circuit of the release relay 358 will be interrupted at contact 360 on the deenergization of the relay 356. The release relay 115 358 then closes at contact 313 an impulse circuit extending through 331 of switch 332 and the stepping magnet 318. At the same time the coupling magnet is energized by a current flowing from the negative pole, through 325, 314, 327, 304 to the positive pole. Immediately after the energization of the coupling magnet 304 by the current flowing through contact 327 this contact is opened by the energization of the relay 326 which is effective 120 125 130

by a current that flows from the positive pole through 329, 326, 314, 325 to the negative pole. By this means the current of the coupling magnet 304 is weakened. The ringing current generator 354 cannot send ringing current to the wipers 372, 373 at this moment because, on the deenergization of the release relay 358, the circuit of the test relay 347 was interrupted at contacts 312 and 360.

10 The stepping magnet 318 now receives stepping impulses during the flowing of which the coupling magnet 304 is energized by a weak current just sufficient to maintain its armature attracted whilst the starting magnet 315 is deenergized. As soon as the shaft section 1 is restored to its normal position with respect to shaft section 2 the off-normal switch 365 is opened whereby the relay 315' is energized in addition to relay 362 so that now the starting magnet 315, which was deenergized by the opening of the contacts 360, 312, is again energized by a current flowing from the negative pole through 330, 334, 315 to the positive pole. 15 The impulses which flow through the stepping magnet 318 now cause the two inter-coupled shaft sections 1 and 2 together with the wipers 372-375 to rotate step-by-step until the wipers reach their normal position in 20 which they are shown in Fig. 9. At this moment the off-normal switch 332 is opened whereby the stepping magnet 318 is switched off at contact 331 while the starting magnet 315 is switched off at contact 334. The various parts of the connector have now been restored to their normal positions.

25 If the calling subscriber replaces his receiver first the deenergization of the release relay 358 is effected by the short circuiting of the same through contact 320. By this means the restoring operations are initiated to take place in the manner already described so that they need not be repeated.

It will now be assumed that at the moment 30 the negative potential is applied to the test relay 347 in the manner already described the called subscriber is engaged. The test relay 347 will then not be energized and a busy tone current will be sent from the busy tone producer 390 through the coil 391 which is wound on the impulse relay 355. The busy tone current flows from the busy tone producer 390 through contact 340, 344, 352, 391 and back to 390. A secondary busy tone current is then induced in the coils of relay 355 and thus sent to the calling subscriber's station, apprising him of the fact that the wanted line is busy so that he will replace his receiver and the relay 355 will be de-energized and initiate the restoring operations already described.

In Figs 10 and 11 circuits are shown by which the speed at which the wipers are driven up to a desired group of bank contacts may be increased at will and by which

the number of steps or extent of travel that the wipers have to execute, after they have reached the desired bank contact group may be reduced to any desired extent. In Fig. 10 the magnet 4¹ corresponds to the coupling magnet 4, Fig. 8, and 116¹ corresponds to brush 114, Fig. 8. 109¹, 109², etc. correspond to the subgroup relay 109 of Fig. 8. If the wiper 106 of the started switch is to be stopped at the beginning of the fourth group 75 of contacts that is at contact 401 the negative pole, which is ordinarily connected to all long contacts or group contacts, is disconnected from the three group marking contacts 402, 403, 404 located before the group marking contact 400, this being effected by the subgroup relay 109⁴. It is obvious that when the wiper 116¹ travels over the contacts 402, 403, 404 the current flowing through the coupling magnet 4¹ stops flowing as soon as 80 the wiper commences travelling over contact 402 and this cessation of the current continues whilst the wiper travels over 403, 404. The duration of cessation of the flow of current through the coupling magnet 4¹ is therefore the time that the wiper 116¹ requires to travel over the three contacts 402, 403, 404. The wiper 116¹ may therefore be moved over the group marking contacts three times as that as if only one group marking contact 85 like 402 were disconnected from the negative pole.

If the arrangement of the coupling is such that the coupling magnet is to couple the shaft sections when it is energized (instead of de-energized as in Fig. 10) the circuits are modified as shown in Fig. 11 in which 109^a, 109^b, 109^c, etc. denote the subgroup relays, 4² the coupling magnet and 116² the wiper connected to the coupling magnet. If a subgroup relay say 109^d attracts its armature the negative pole is connected to the group marking contacts 402¹, 403¹, 404¹ and the coupling magnet 4² receives current when the brush commences travelling over the first of these 100 three contacts. The brushes are brought to a standstill when they reach the contact 400¹, it being assumed that the time that the magnet 4² requires to attract its armature is equal to the duration of travel of the brush 116² 105 over the three contacts 402¹, 403¹, 404¹.

In this manner the speed at which the wipers are driven off to the proper group of the bank contacts may be made three times as great as if the potential were taken off 110 (Fig. 10) or applied (Fig. 11) from or to only one of the group marking contacts situated before the desired contact group. By arranging the circuits so that a single subgroup relay effects a still greater number of group 115 marking contacts the speed of travel of the brush 116 may be increased to a still greater extent. Conversely the number of contacts sets in a subgroup may be decreased so that after the wiper has reached the desired con- 120

tact group a number of steps or the extent of its travel is decreased say from ten steps (or a corresponding distance) to three steps or even one step.

5 Figs. 12 to 15 show a modified switch in which only two magnets instead of three are employed. Besides, the contact bank which is not shown in Fig. 12 has a different arrangement of its soldering tabs, this arrangement being shown in Figs. 16 and 17.

In Fig. 12 604 is the coupling magnet and 618 the stepping magnet which corresponds to the magnets 4 and 18 of Fig. 1, the third magnet being omitted. The disk 610 attached to the brush carrier is shaped as shown in Fig. 14. The disk has 9 openings 611 and a tenth opening 12 which is somewhat wider than the openings 611. In the normal position of the switch the coupling member 631 is in engagement with the opening 612 and holds the stop 613 out of engagement with the disk 610 as illustrated in Fig. 15. When the coupling member 631 is pulled downwards by the magnet 604 the stop 613 which has an oblique bottom surface 614 rides up onto the disk 610 and slides on its outer ring 615. In the operation of the switch the disk 610 fixed to the brush carrier will be stopped by the coupling member 631 rising onto one of the openings 611 when the brushes will be stopped at the beginning of the desired group of bank contact sets of the line finder, group selector or connector as the case may be. When the switch is restored the coupling member 631 is pulled out of the opening again and the disk 610 then rotates further until the opening 612 reaches the movable stop 613. This stop then drops into the opening 612 and when the leg 616 reaches the stop 613 the disk 610 will be stopped. The spring of the switch is then rewound, or the normal relationship between the rotary shaft on which the hollow shaft or brush carrier is journaled, is then restored by the stepping wheel 629 being stepped round by the stepping pawl until the member 631 reaches the opening 612, a switch consisting of the springs 635, 636 is opened to deenergize the magnet 604 and at the moment the coupling member 631 registers with the opening 612, another switch consisting of the springs 636, 637 is opened to deenergize the stepping magnet 618. The coupling member 631 thus enters the opening 612 and lifts the stop 613 to its normal position. The switches consisting of the springs 635, 636 are actuated by a cam 638 with cam surfaces 639, 640. The cam 638 is fixed to the stepping wheel 629. Shortly before the coupling member 631 reaches its normal position, that is to say shortly before it registers with the opening 612, the spring 641 rides up onto the cam surface 639. When the coupling member 631 registers with the opening 612 the spring 641 rides up onto the

surface 640. By this means the switches 635, 636 and 636, 637 are opened in succession.

In the operation of setting the brushes of the switch onto the desired group of bank contacts the coupling member 631 is controlled in a line finder in a manner already described in connection with the switch 100, Fig. 8. When the modified switch is used as a connector the long group designating contacts and the short contacts between them which are used in the switch 200 are replaced by an interrupter consisting of springs 650, 651 and effected by the projections 652, 652', 652'' etc. of the disk or spider 610. The group selecting impulses are sent through the springs 650, 651 into the coupling magnet 604, each group selecting impulse causing the coupling magnet 631 to be drawn out of engagement with the spider 610. When the spider is moved by its propelling agent or spring the interrupter 650, 651 is opened through the spring 660 entering a recess such as 655 between 2 projections 652. At each new current impulse the spring 660 will have ridden up onto a new projection 652. It is thus seen that the projection 652 corresponds in a sense to the short contacts like 276, 277, switch 200, Fig. 8, and the recesses 655 correspond to the long dead contacts between the short contacts, switch 200, Fig. 8. The pawl 630 normally engages with a tooth of the wheel 629. Since the pawl strikes against a stop 670 the wheel 629 is normally prevented from rotating in the direction at which it is stepped when the pawl 630 is operated by the armature 671 of the magnet 618. The pawl 630 is connected to the armature 671 by a lever or arm 672. The rear end of the arm terminates in a member 673 bent at right angles through the arm 672 and attached to the armature 671 by screws 674, 675. The member 673 has oblong holes so that the arm 672 can be adjusted in the directions indicated by the arrow 676. By thus adjusting the arm 672 and by also shifting the stop or block 670 the pawl 630 may be advanced in the direction of the arrow 677 or moved back in the opposite direction and the position that the brushes occupy on any bank contact may thus be altered at will, i. e. the point at which the brushes touch a contact when the pawl 630 is in engagement with the wheel 629 as shown may be advanced or displaced rearwardly at will. This adjustment or correction of the brush position on a bank contact can be effected without altering the gap or stroke between the armature and the pawl faces of the stepping magnet. The arm 672 with its pawl 630 are urged in the direction of the arrow 679 by the spring 678 whose tension may be adjusted by the screw latch 680.

In the foregoing description mention has been made of the pressure exerted by the end

of the central shaft on its end bearing when the coupling magnet is energized. This pressure can be minimized as hereinbefore described by cutting a resistance into the coupling magnet circuit when it has attracted its armature. To eliminate this pressure and the resultant friction altogether the coupling magnet, instead of being fixed to the switch frame, may be mounted on the central switch or attached to the stepping wheel so as to rotate therewith.

To enable the banks of several switches mounted side by side to be interconnected in a simple manner by bare wires, the bank contacts are provided with tabs of the kind illustrated in Figs. 16 and 17. In Fig. 16, 670 is the top contact of a set of three bank contacts. The contact 670 has a soldering tab in the form of a projection 671. The contact beneath the bank contact 670 has a soldering tab 672 which is shorter than 671. The third contact corresponding to 670 has a tab in the form of a still shorter projection 637 protruding from the contact bank mounting 674. It will be noted that the tabs 672, 673 project beyond the lateral edge of the narrow part of the tab 671. The corresponding set of bank contacts 671', 672', 673', Fig. 17 in a switch mounted beside the switch shown in Fig. 16 can therefore be multiply connected by bare wires 674, 675, 676 stretched straight from one soldering tab to another such as the wire 674 stretched from the tab 671' to 671. It will be apparent that a bank contact set may consist of practically any number of bank contacts without any difficulty in the interconnection of adjacent corresponding sets of bank contacts by bare wires or wire ribbons arising.

I claim:

1. In a circuit switching mechanism, two coaxial shaft members adapted to be rotated in one and the same direction, an electromagnetically operated stepping pawl for holding one of said members against rotation, an electromagnet having an armature, and means controlled by the armature of said electromagnet for normally holding the other member against rotation.

2. In an electric circuit switching mechanism, a shaft, a stepping wheel fastened to said shaft, a stepping pawl normally holding said wheel against rotation, a hollow shaft journaled upon said first-mentioned shaft, an electromagnet having an armature, and means controlled by said armature for holding said hollow shaft against rotation.

3. In an electric circuit switching mechanism, a shaft, a stepping wheel attached to said shaft, an electromagnetically operated stepping pawl normally holding said wheel against rotation, a hollow shaft journaled upon said shaft, an electromagnet having an armature, means controlled by said armature for holding said hollow shaft against rotation, and a coupling member carried by one of said shafts when either shaft is rotated.

4. In an electric circuit switching mechanism, a shaft, a stepping wheel attached to said shaft, a stepping pawl for normally holding said wheel against rotation, a hollow shaft, journaled against said first-mentioned shaft, a spider carried by said hollow shaft, an electromagnet having an armature engaging said spider to hold the hollow shaft against rotation, and a coupling member carried by said first-mentioned shaft and cooperating with said spider.

5. In an electric circuit switching mechanism for automatic telephone systems, a rotatable brush adapted to execute separate group and terminal selecting movements, two coaxial shafts, one arranged within the other, a wheel attached to each shaft, one of said wheels adapted to control the group selecting movement and the other of said wheels adapted to control the terminal selecting movement of said brush, and a coupling member pivoted to one of said wheels having its free end in cooperative relation with the other of said wheels.

6. In an electric circuit switching mechanism for automatic telephone systems, a brush adapted to execute separate group and terminal selecting movements, two shafts, one adapted to control the group selecting movement and the other the terminal selecting movement of said brush, means for turning said shafts in the same direction, a notched disc mounted on one of said shafts, an electromagnet having an armature and a pivotal mounting for said armature on the other one of said shafts so that its free end cooperates with said notched member.

7. In an electric circuit switching mechanism for automatic telephone systems, a brush adapted to execute separate group and terminal selecting movements, two shafts, one for controlling the group selecting movement of said brush and the other for controlling the terminal selecting movement of said brush, a notched member affixed to one of said shafts, an electromagnet, an armature for said magnet having a tongue cooperating with said notched member and a pivotal mounting for said armature on the other of said shafts.

8. In an electric circuit switching mechanism, two shaft members, a contact bank having sets of contacts arranged in parallel rows, wipers carried by one of said shaft members cooperating with said bank, means for rotating said shafts in the same direction, and a spiral spring interconnecting said members wound up during the rotation of one of said shaft members.

9. In an electric circuit controlling switch, a contact bank having sets of contacts arranged in parallel rows, a wiper, means for operating said wiper to cooperate with said

contact bank, a stopping magnet for said wiper, means for supplying current to said stopping magnet depending on the speed at which the wiper is moved and the number of bank contacts traversed thereby.

10. In an electric circuit controlling switch, a wiper, a wiper-carrying member, means for applying driving force to said member, a detent for said member, means responsive to the movement of said member for actuating said detent, and an electromagnet for operating said detent depending on the position of said member.

11. In an electric circuit controlling switch, a wiper, a carrying member therefor, a spring adapted to cause the rotation of said member, a detent for said member actuated in response to a certain movement of said member, an electromagnet for operating said detent, and means depending on the movement of said wiper for actuating said magnet.

12. In a circuit switching mechanism, two coaxial shaft members adapted to be rotated in one and the same direction, an electromagnetically operated stepping pawl for holding one of said members against rotation, an electromagnet having an armature, means controlled by the armature of said electromagnet for normally holding the other member against rotation, an electric circuit for energizing said electromagnet, and a remotely controlled relay armature for controlling said electric circuit.

13. In an electric circuit switching mechanism, a shaft, a stepping wheel fastened to said shaft, a stepping pawl normally holding said wheel against rotation, a hollow shaft journaled upon said first-mentioned shaft, an electromagnet having an armature, means controlled by said armature for holding said hollow shaft against rotation, an electric circuit for energizing said electromagnet and a remotely controlled relay armature for controlling said electric circuit.

14. In an electric circuit switching mechanism, a shaft, a stepping wheel attached to said shaft, an electromagnetically operated stepping pawl normally holding said wheel against rotation, a hollow shaft journaled upon said shaft, an electromagnet having an armature, means controlled by said armature for holding said hollow shaft against rotation, a coupling member carried by one of said shafts when either shaft is rotated, an electric circuit for energizing said electromagnet, and a remotely controlled relay armature for controlling said electric circuit.

15. In an electric circuit switching mechanism, a shaft, a stepping wheel attached to said shaft, a stepping pawl for normally holding said wheel against rotation, a hollow shaft journaled against said first-mentioned shaft, a spider carried by said hollow shaft, an electromagnet having an armature engaging said spider to hold the hollow shaft

against rotation, a coupling member carried by said first-mentioned shaft and cooperating with said spider, an electric circuit for energizing said electromagnet, and a remotely controlled relay armature for controlling said electric circuit.

16. In an electric circuit switching mechanism, two shaft members, a contact bank, wipers carried by one of said shaft members cooperating with said bank, means for rotating said shafts in the same direction, a spiral spring interconnecting said members wound up during the rotation of one of said shaft members, an electric circuit for energizing said electromagnet, and a remotely controlled relay armature for controlling said electric circuit.

17. In an electric circuit controlling switch, a contact bank, a wiper, means for operating said wiper to cooperate with said contact bank, a stopping magnet for said wiper, means for supplying current to said stopping magnet depending on the speed at which the wiper is moved and the number of bank contacts traversed thereby, an electric circuit for energizing said electromagnet, and a remotely controlled relay armature for controlling said electric circuit.

18. In an electric circuit controlling switch, a wiper, a wiper-carrying member, means for applying driving force to said member, a detent for said member, means responsive to the movement of said member for actuating said detent, an electromagnet for operating said detent depending on the position of said member, an electric circuit for energizing said electromagnet, and a remotely controlled relay armature for controlling said electric circuit.

19. In an electric circuit controlling switch, a wiper, a carrying member therefor, a spring adapted to cause the rotation of said member, a detent for said member actuated in response to a certain movement of said member, an electromagnet for operating said detent, means depending on the movement of said wiper for actuating said magnet, an electric circuit for energizing said electromagnet, and a remotely controlled relay armature for controlling said electric circuit.

20. In a circuit switching mechanism, two coaxial shaft members adapted to be rotated in one and the same direction, an electromagnetically operated stepping pawl for holding one of said members against rotation, an electromagnet having an armature, means controlled by the armature of said electromagnet for normally holding the other member against rotation, and a remotely controlled oscillatory relay armature for sending current impulses through said electromagnet.

21. In an electric circuit switching mechanism, two shaft members, a contact bank, wipers carried by one of said shaft members cooperating with said bank, means for rotat-

ing said shafts in the same direction, a spiral spring interconnecting said members wound up during the rotation of one of said shaft members, and a remotely controlled oscillatory relay armature for sending current impulses through said electromagnet.

22. In an electric circuit controlling switch, a contact bank, a wiper, means for operating said wiper to cooperate with said contact bank, a stopping magnet for said wiper, means for supplying current to said stopping magnet depending on the speed at which the wiper is moved and the number of bank contacts traversed thereby, and a remotely controlled oscillatory relay armature for sending current impulses through said electromagnet.

23. In an electric circuit controlling switch, a wiper, a wiper-carrying member, means for applying driven force to said member, a de-

tent for said member, means responsive to the movement of said member for actuating said detent, an electromagnet for operating said detent depending on the position of said member, and a remotely controlled oscillatory relay armature for sending current impulses through said electromagnet.

24. In an electric circuit controlling switch, a wiper, a carrying member therefor, a spring adapted to cause the rotation of said member, a detent for said member actuated in response to a certain movement of said member, an electromagnet for operating said detent, depending on the movement of said wiper for actuating said magnet and a remotely controlled oscillatory relay armature for sending current impulses through said electromagnet.

In testimony whereof I affix my signature.

FRITZ ALDENDORFF.
